UNITED STATES PATENT OFFICE.

WILLIAM C. LEWIS, OF WASHINGTON, DISTRICT OF COLUMBIA.

FIREPROOF FLOOR CONSTRUCTION.

SPECIFICATION forming part of Letters Patent No. 732,091, dated June 30, 1903.

Application filed August 12, 1902. Serial No. 119,387. (No model.)

To all whom it may concern:

Be it known that I, WILLIAM C. LEWIS, a citizen of the United States, residing at Washington, in the District of Columbia, have invented certain new and useful Improvements in Fireproof Floor Construction, of which the following is a specification.

My invention relates to an improvement in fireproof floor construction; and the object of ¹⁰ the same is to provide a simple form of construction which will be an economical fire-resisting and load-supporting floor covering and protecting the girders.

With these and other objects and ¹⁵ advantages in view the invention consists in the novel and useful arrangement and combination of parts described and claimed in the following specification and illustrated in the accompanying drawings.

²⁰ In said drawings, Figure 1 is a transverse sectional view of a floor and ceiling constructed according to my invention. Fig. 2 is a detail view. Fig. 3 is a detail view of a modified form of tension member.

²⁵ In the drawings like letters of reference designate like parts in the views.

Between the floor-girders A, shown here as I-beams, and resting on the lower flanges thereof is placed a suitable tension member ³⁰ B, of reticulated metal, such as expanded metal.

This tension member extends over the area of the floor to be constructed and may be in one or several strips or widths to form a web. The lower flanges of the I-beams ³⁵ are also wrapped with strips of this metal, as shown at C. A mass of suitable plastic material, such as concrete, is then laid between the I-beams and reaches from a level below the lower flanges thereof to a suitable height

⁴⁰ up above the tension member. This plastic material embeds the tension member B therein, as well as the strips wrapped around the lower flanges on the girders, and when it "sets" forms a solid layer D and a ceiling, ⁴⁵ covering the bottom of the I-beams. This layer, reinforced by the tension member, is sufficient for the support of the floor-loads and serves as a base upon which to build up the floor. To complete the floor, I employ

⁵⁰ blocks E, made of some suitable light plastic material, such as a composition of cinders and cement molded into blocks of suitable

size and shape and allowed to set and harden before use. These blocks may be sized and shaped so that they may be used in the ⁵⁵ construction of any fireproof floors—that is, they will be adapted to general use and not necessarily molded for a particular construction of floor. They are laid upon the base D from I-beam to I-beam to cover the ⁶⁰ area of the floor, and the seams or meeting edges may be finished with cement, thus producing a fireproof floor with a hard surface, which throughout is light and yet possesses all the tensile strength which may be necessary ⁶⁵ to support the floor-loads. This construction combines few parts and is efficient and durable.

The objections to floors employing a cinder filling are obviated, and advantages over a ⁷⁰ solid cement or tile floor are too apparent to need specification.

In Fig. 3 I have shown a tension member in the form of a spanner-rod B', of which a series are laid from girder to girder and rest ⁷⁵ upon the lower flanges thereof. These rods may be smooth or irregular of surface and when embedded in the layer of plastic material will also support the floor-loads. It may be stated here that the ceiling, though shown ⁸⁰ in Fig. 1 as built up from below the level of the I-beams, may also be built up from the level thereof without in any way changing the construction herein outlined.

Having thus fully described my invention, ⁸⁵ what I claim as new, and desire to secure by Letters Patent of the United States, is—

1. In fireproof floor construction the combination with floor-girders, of a concrete layer or base extending between and supported by ⁹⁰ the girders and a floor of blocks resting on said layer or base and filling the space to the top of the girders.

2. In fireproof floor construction, the combination with floor-girders, a tension member ⁹⁵ extending from girder to girder and resting on the lower flanges thereof, a layer of plastic fire-resisting material extending from girder to girder and embedding therein the said tension member, and a continuous layer of blocks ¹⁰⁰ of fire-resisting material, resting upon the layer of plastic material and extending from girder to girder, substantially as described.

3. In fireproof floor construction, the com-

combination with floor-girders, a tension member extending from girder to girder and consisting of an expanse or web of reticulated metal, a layer of plastic fire-resisting material extending from girder to girder and embedding 5 therein the said web of reticulated metal, and a continuous layer of blocks resting upon the said layer of plastic material and extending from girder to girder, said blocks being com-

posed of cement and cinders, molded into shape and allowed to "set," substantially as described.

In testimony whereof I affix my signature in presence of two witnesses.

WILLIAM C. LEWIS.
